UNITED STATES PATENT OFFICE.

HENRY A. WEIHMAN, OF PHILADELPHIA, PENNSYLVANIA, ASSIGNOR TO
SIMONS, BROTHER & CO., OF SAME PLACE.

DESIGN FOR A THIMBLE.

SPECIFICATION forming part of Design No. 21,844, dated September 6, 1892.

Application filed February 20, 1892. Serial No. 422,298. Term of patent 14 years.

To all whom it may concern:

Be it known that I, HENRY A. WEIHMAN, a citizen of the United States, residing at Philadelphia, in the county of Philadelphia, in the State of Pennsylvania, have invented and produced a new and original Design for Thimbles, of which the following is a specification, reference being had to the accompanying drawings, illustrating the design.

Figure 1 is a side elevation of a thimble having my design applied thereto, and Fig. 2 is a diagrammatic plan view of the same with the metal of the thimble laid flat.

A is the upper portion of the thimble, with the usual roughened surface.

B is the lower bell portion, with the representation of a crack or fracture b.

C is a band between the top portion A and

the lower bell part B, which may contain a suitable motto.

The essential feature of the design is the representation of the bell with the upper roughened surface.

What I claim as new, and desire to secure by Letters Patent, is—

The design for a thimble, as herein described and shown, consisting of the representation of a "Liberty bell" having the upper roughened surface A.

In testimony of which invention I have hereunto set my hand.

HENRY A. WEIHMAN.
